UNITED STATES PATENT OFFICE.

JOHN EDWIN BUTLER, OF COWELL, CALIFORNIA.

BED-SUPPORT.

1,247,369.

Specification of Letters Patent. Patented Nov. 20, 1917.

Application filed June 20, 1917. Serial No. 175,855.

To all whom it may concern:

Be it known that I, JOHN EDWIN BUTLER, a citizen of the United States, residing at Cowell, in the county of Contra Costa and 5 State of California, have invented new and useful Improvements in Bed-Supports, of which the following is a specification.

My invention is an improvement in bed supports, and has for its object to provide 10 mechanism of the character specified, especially adapted for use in hospitals and sick rooms, for preventing the patient, when sitting up, from slipping down toward the foot of the bed.

15 In the drawings:

Figure 1 is a transverse vertical section of a bed provided with the improved support;

Fig. 2 is a section on the line 2—2 of Fig. 1, looking in the direction of the arrow adjacent to the line; and

Fig. 3 is a perspective view of the hinged clamp.

The present embodiment of the invention is shown in connection with a bed 1, the said 25 bed having the usual side rails 2. A plate 3 is provided of sufficient length to extend almost across the bed, and the ends of the plate are supported by the clamps, to be later described, just above the mattress 4.

30 The support comprises a pair of bars 5, which are spaced apart from each other, and are connected by a series of cross bars 6, said cross bars being riveted to the bars 5. Each of the cross bars 6 is extended at one 35 end at approximately a right angle to the body of the bar, as indicated at 7, and these extended portions are arched, being bent back upon the bodies of the bars 6 and secured thereto by rivets 8 or the like. Thus 40 each of the bars 6 has a wicket shaped or arched portion above one of the bars 5, and these wicket shaped or arched portions are in register. The end bars 6 are also extended at the opposite end, and bent at a right 45 angle to the bodies of the bars as indicated at 9, and are then bent down, as indicated at 8, upon the bodies of the bars, being secured thereto by the rivet 8, as shown.

A resilient structure is thus provided, 50 composed of the bars 6 and extensions 7, and these extensions 7 are connected by a curved plate 11, said plate connecting all the extensions and being riveted thereto as shown. The plate 3 is received at its ends between 55 marginal ribs 12 on bracket plates 13, which

are supported by the side rails 2 of the bed. The plate has a threaded stem 14, and the bracket an opening through which the stem is passed, and a wing nut 15 engages the stem above the plate. Each of these brackets 60 13 is arched, as shown, outwardly to extend outside of the mattress and then above the same, and at its lower end each bracket has an outward extension 16, which is one of the leaves of a hinge, and the said leaf is adapted to rest upon the horizontal portion of the angular bed rail. The other leaf 17, which is hinged to the leaf 16, is adapted to fit outside the vertical portion of the angular rail, and means is provided for clamping this leaf 17 to the rail. The said means 65 comprises a clamping plate 18 fitting outside of the hinged leaf 17, and having a hook shaped extension 19, which is adapted to engage beneath the edge of the rail, as shown. 70

This clamping plate has a series of vertical slots 20, and the hinged leaf has threaded openings 21 registering with the slots. A set screw 22 is passed through one of the 80 slots and engages one of the threaded openings and the side rail to clamp the parts together.

An angular flange plate 23 is secured to each bracket 13 at the angle formed between the said bracket and the hinged leaf 16, and this flange plate is adapted to engage beneath the horizontal portion of the side rail, as shown in Fig. 1, to prevent upward movement of the hinged leaf 16. 85

The bar 5 adjacent to the plate 3 is hinged 90 to the said plate by means of hinges 3^a, in order that the support may take the position of Fig. 1 or the position of Fig. 2. In the former position the support is used as a knee rest for supporting the knees, while in the latter position it is used as a foot rest. In use, the bracket plates are secured to the rails by first engaging the flange plates 23 beneath the horizontal portions of the rails. The hinged leaves 17 are 95 then turned down upon the vertical portions of the side rails and the clamping plates 18 are placed. The plate 3, carrying the resilient support, is then inserted between the guides 12 of each bracket and the parts are bolted together. In practice, the pillow is first placed beneath the patient's knees and then the resilient support, and the support is then connected up with the brackets. When used as a foot rest the 100 105 110

pillow is placed against the cross bars 6 while, when in use as a knee rest, the pillow is placed as shown in Fig. 1.

In practice, the parts are of cold rolled 5 steel, and are enameled white. The plate 11, in addition to reinforcing the device, prevents the pillow from being forced down into the space between the arches. It will be understood that the supports may be 10 arranged in either the position shown in Fig. 2 or with the cross bars 6 on the plate 3.

I claim:

1. A device of the character specified, comprising a pair of spaced parallel strips, 15 cross bars connecting the strips at spaced intervals, each cross bar having at one end an extension of substantially U-shape, the free end of each extension being secured to the body of the bar near the opposite strip, 20 each of the end cross bars having an extension at the opposite end extending at right angles to the bar in the same direction as the first named extension and then bent backward and secured to the body of the bar, a plate to which one of the cross bars is hinged, and brackets detachably connected with the ends of the plate and having means for engaging the side rails of the bed to support the plate above the mattress, each 25 of the clamps being arched to extend outside the mattress and having at the end adjacent to the side rail an outward extension, and a flange plate for engaging beneath the inner edge of the side rail, the extension extending to the outer edge of the rail, a leaf 30 hinged to the extension and adapted to fit the outer face of the side rail, and means for clamping said leaf to the rail.

2. A device of the character specified,

comprising a pair of spaced parallel strips, 40 cross bars connecting the strips at spaced intervals, each cross bar having at one end an extension of substantially U-shape, the free end of each extension being secured to the body of the bar near the opposite strip, 45 each of the end cross bars having an extension at the opposite end extending at right angles to the bar in the same direction as the first named extensions and then bent backward and secured to the body of the bar, a plate to which one of the cross bars is hinged, and brackets detachably connected with the ends of the plate and having means for engaging the side rails of the bed to support the plate above the mattress. 50

3. A device of the character specified, comprising a pair of spaced parallel strips, cross bars connecting the strips at spaced intervals, each cross bar having at one end an extension of substantially U-shape, the free end of each extension being secured to the body of the bar near the opposite strip, each of the end cross bars having an extension at the opposite end extending at right angles to the bar in the same direction as 55 the first named extensions and then bent backward and secured to the body of the bar.

4. A device of the character specified comprising a pair of spaced strips, cross bars connecting the strips at spaced intervals and 60 arched in the same direction, and means for connecting the support to the opposite rails of a bed.

5. A device of the character specified comprising a pair of spaced strips, cross bars connecting the strips at spaced intervals and 65 arched in the same direction.

JOHN EDWIN BUTLER.
